UNITED STATES PATENT OFFICE

PETER I. HARVEY, OF AMSTERDAM, NEW YORK, ASSIGNOR OF ONE-HALF
TO AUGUSTUS CLARK AND PERRY KLINE, OF SAME PLACE.

FEED-GUIDE ATTACHMENT FOR KNITTING-MACHINES.

SPECIFICATION forming part of Letters Patent No. 279,380, dated June 12, 1883.

Application filed November 11, 1882. (No model.)

To all whom it may concern:

Be it known that I, PETER I. HARVEY, of Amsterdam, in the county of Montgomery and State of New York, have invented a new and 5 Improved Feed-Guide Attachment for Knitting-Machines, of which the following is a full, clear, and exact description.

The object of my invention is to provide a new and improved feed-guide attachment for 10 knitting-machines, whereby one of the threads can be passed above the other at will, the raised thread showing on the outer surface of the knitted fabric.

This invention is an improvement on the 15 circular-knitting machine for which Letters Patent No. 253,531 were issued to myself and to my assignees, Augustus Clark and Perry Kline, of Amsterdam, New York, on February 14, 1882.

Reference is to be had to the accompanying 20 drawings, forming a part of this specification, in which similar letters of reference indicate corresponding parts in both the figures.

Figure 1 is a plain view of part of a knitting- 25 machine provided with my improved feed-guide attachment. Fig. 2 is a side view of the feed-guide attachment, showing the manner in which it is attached to the feed-stand.

My invention is applicable to the ordinary 30 upright circular-knitting frames, which frames are well understood by those skillful in the art of knitting, and it will not be necessary to describe that construction and arrangement.

35 A is a needle-cylinder in which the barbed needles B are secured.

E is a cam constructed substantially as shown and permanently secured to the lower outer part of the needle-cylinder. I usually employ 40 one of those cams on a cylinder; but two or more may be used, as occasion may require.

The feed-stand F has attached thereto the cloth-presser wheel G, the loop or sinker-burr H, and the fixed feed-guide I, and are all adjustable in their relative positions in the usual manner and on the same pivot which secures the thread-guide I to the feed-stand F. An additional feed-guide, W, is pivoted to the feed- 45 stand F, which pivoted feed-guide W is parallel with the fixed feed-guide I, but has its end

at the needle-cylinder inclined toward the corresponding end of the feed-guide I, as shown in Fig. 1, the end of the feed-guide W projecting slightly beyond the end of the feed-guide I. A spring, V, surrounding the pivot of the feed-guide W, presses the said feed-guide W in a horizontal position. 55

In place of the spring V, any other suitable device can be used which will keep the feed-guide W in a horizontal position or return it 60 to the same after it has been moved out of the said horizontal position. The pivoted feed-guide W is provided with a downwardly-projecting arm, U.

On the stand L, I place the cam ratchet-wheel M, which is provided with one or more cams, c. Upon the ratchet-wheel I place the adjustable cam-lever f', which vibrates upon a stem, and is held in its normal position by the spring l. The combined ratchet and cam 65 wheel M is prevented from revolving backward by the pawl-spring m. As the cam c presses the lever p forward the end of the latter rides upon the outer face of the cam until said end has been passed by the cam, and the lever p 70 transmits motion to a lever on the opposite side of the needle-cylinder, as described in my Patent No. 253,531. The yarn is fed by the loop-wheel beneath the barbs of the needles. 75

The operation is as follows: When the cylinder A rotates it causes the lever f', by the cam E, to rotate the combined cam and ratchet M in the direction of the arrow, whereby the cam c will press one end of the compound-lever p in the direction toward the cylinder, 80 thereby pressing the middle joint of the lever p in the direction from the cylinder A, the other end being pressed toward the cylinder A. If the lever p is moved toward the cylinder A, it strikes against the arm U of the pivoted feed-guide W and raises that end of the feed-guide 85 from which the thread passes to the knitting-cylinder. As long as the said feed-guide W is raised the thread passing through the said feed-guide W will show on the outside of the fabric, 90 and as soon as the lever p is moved in the direction from the cylinder A by a spring or other suitable device, the arm U of the feed-guide W will be released and the spring V will 95 throw the feed-guide W back into the horizontal 100

tal position, and the thread passing through the feed-guide I will show on the outer surface of the fabric. Thus, by varying the number, size, and arrangement of the cams E and e various different designs can be produced in the knitted fabric.

Having thus fully described my invention, I claim as new and desire to secure by Letters Patent—

1. A needle-cylinder provided with one or more cams, E, combined with the fixed feed-guide I and the pivoted feed-guide W, having an arm, U, and with devices for moving the pivoted feed-guide by the action of the cams E

on the said cylinder A, substantially as herein shown and described, and for the purpose set forth.

2. The needle-cylinder provided with one or more cams, E, combined with the fixed feed-guide I and the pivoted feed-guide W, having the arm U, the compound lever p, the combined cam and ratchet wheel M, and the cam-lever f', substantially as herein shown and described, and for the purpose set forth.

PETER I. HARVEY.
